UNITED STATES PATENT OFFICE

163,156

MILK CAN COVER RACK

George C. Zarling, Jackson, Wis.

Application March 31, 1950, Serial No. 8,898

Term of patent 3½ years

(Cl. D44—29)

To all whom it may concern:

Be it known that I, George C. Zarling, a citizen of the United States and resident of Jackson, in the county of Washington and State of Wisconsin, have invented a new, original, and ornamental Design for Milk Can Cover Rack, of which the following is a specification, reference being had to the accompanying drawing, forming part hereof:

The sole figure is a perspective view of a milk can cover rack, showing my new design.

I claim:

The ornamental design for a milk can cover rack, as shown.

GEORGE C. ZARLING.
